UNITED STATES PATENT OFFICE

107,777

DESIGN FOR A COMBINED CIRCULATOR FAN AND TABLE

William L. Kisling, St. Louis, Mo.

Application October 18, 1937, Serial No. 72,291

Term of patent 7 years

To all whom it may concern:

Be it known that I, William L. Kisling, a citizen of the United States, residing at St. Louis, State of Missouri, have invented a new, original, and ornamental Design for a Combined Circulator Fan and Table, of which the following is a specification, reference being had to the accompanying drawing, forming part thereof.

In the drawing:

Figure 1 is a side view of a combined circulator fan and table showing my design.

Figure 2 is a top plan view thereof.

I claim:

The ornamental design for a combined circulator fan and table, as shown.

WILLIAM L. KISLING.
